COMBINED DATA KEYBOARD ENTRY AND DISPLAY CONSOLE

Clarence D. Zierhut and Gene D. Vedder, Granada Hills,
Calif., assignors to Lexitron Corporation, Burbank,
Calif.

Filed July 19, 1971, Ser. No. 164,201

Term of patent 14 years

Int. Cl. D14—02

U.S. Cl. D26—5 C

FIG. 1.

FIG. 2.

FIG. 3.

FIG. 1 is a front perspective view of a combined data keyboard entry and display console embodying our new design;

FIG. 2 is a top view of the console of FIG. 1; and

FIG. 3 is a right side view of the console of FIG. 1. We claim:

The ornamental design for a combined data keyboard entry and display console, substantially as shown.
